UNITED STATES PATENT OFFICE.

NEIL L. CAMPBELL, OF SALEM, NEW JERSEY, ASSIGNOR TO JOHN B. CAMPBELL MANUFACTURING COMPANY, INC., OF SALEM, NEW JERSEY, A CORPORATION OF NEW JERSEY.

BLOCK-PRINTED FELT-BASE RUG AND METHOD OF MAKING SAME.

Application filed November 26, 1923. Serial No. 677,014.

The principal objects of the present invention are to effect a marked economy in the cost of blocks and machinery and in the printing operation; to provide for a wide range of latitude in the matter of design; to facilitate changing the designs on the machine; to reduce the number of blocks and frames required; to effect a saving in the individual blocks; to entirely eliminate border blocks; and to obtain given or required color effects with the use of much fewer blocks.

In the practice of the method of the present invention the face of the impregnated felt base is completely covered by coating it with a composition of paint and this complete coating of paint composition is appropriate for and is the ground of the border of felt base linoleum rugs or is the border itself. Rug centers, usually in solid color or design, are printed on the center portion of this coating with a block or blocks of less effective length than the width of the carpet leaving unprinted margins at each side and interrupting such printing at intervals by putting a block out of action to provide unprinted crosswise ranging stripes constituting end margins, then, if desired, continuously printing the carpet with a block or blocks of the same effective length as the width of the carpet, providing a broken pattern on the two tones of which one is due to rug center printing and of which the other is due to coating, and finally cutting the carpet at the center of the stripes to provide rugs or mats. A rug or mat of the invention may be said to comprise a felt base primarily coated all over its face with a paint composition providing a border ground or tone and having on the top of the central portions of said coating a rug center, usually of one color or solid design, formed by printing thus providing another tone, and, if desired, having on the top of the printed center and also on the top of the exposed border coating a broken pattern or patterns formed by printing on the top surfaces of the coating and rug center printing.

In further describing the invention reference will be made to the accompanying drawings which are diagrammatic and schematic and in which

Figure 1 may be said in a general way to be a plan view of a block of about the width

of the carpet and of a block of less width than the carpet shown as arranged beside it but independently movable of it, and

Fig. 2 may be said to be a plan view of a carpet produced according to the invention and adapted to be cut up into rugs embodying features of the invention.

Referring to the drawings the entire surface of the carpet 1 is coated with a composition of paint prior to its introduction into a block or linoleum printing machine, and this coating is of a color adapted to constitute what may be called a border ground or one tone. On top of this coating the block or blocks of the printing machine print rug centers 2, which may of course be of any pattern or design and which usually are of a solid color or colors adapted to produce the other tone in cases where two-tone rugs are printed. The block or blocks 3 which print the rug centers are shorter than the width of the carpet and operate upon its central portion leaving the carpet face exposed at each edge as at 4, to permit the coating to constitute the border or border ground. Between rug centers as 2, 2^a and 2^b, the blocks 3 are held out of action, thus leaving the coating or border ground exposed so that when the carpet is cut as on the dotted lines there is produced a number of rugs or mats each having as a border part of the original coated surface of the carpet and having block printed rug centers. So far the invention has been described as if there were but two colors, one the coating on the carpet being a border and the other the printed rug center. However, additional block or blocks 5 of the full width of the carpet may be employed and they will print a pattern on the border and rug center including the spaces between the rug centers, thus as indicated at the right in Fig. 2 there can be produced what in general may be called a border tone, a rug center, and a pattern all over both. Those skilled in the art will understand that each block 3 will in general print a solid color but that is not in all cases necessary and that the block or blocks 5 will usually print an allover pattern like, for example spots, but that is not in all cases necessary. To further explain the invention it may be said that the blocks are usually eighteen inches wide and

seventy-two inches long so that, by making

the blocks 3, fifty-four inches long, disposing them symmetrically with the center of the machine and holding or otherwise preventing them from printing at the ends of the 5 rugs, each rug will have a nine inch border all around although no border blocks are employed. In the matter of color there is of course great latitude because the number of blocks can be increased or diminished but 10 evidently the color adaptation and utilization of the coating of paint on the face of the carpet for the border greatly increases the color effects that can be produced with a given number of blocks, thus simplifying 15 and reducing the size or number of frames of the printing machine and also facilitating and cheapening the printing operation. No border blocks are required and their cost is therefore saved and very good effects can be 20 produced by the employment of blocks which are comparatively cheap to cut or make.

In addition to the blocks of which two, 25 3 and 5 are illustrated, but of which the number may be increased, and in fact the block 5 may be omitted, there can be also provided line top print and masker blocks as will be readily understood, and the line and top print blocks may be adapted to 30 print between and on top of the border and the rug center and in any other location that may be desired. For example there is shown at the left in Fig. 2 a pattern of spots printed by a block 3 on top of a solid center printed by other blocks 3 on top of the primary coating.

Obviously modifications may be made in details of procedure and in mere matters of form without departing from the spirit of 40 the invention which is not limited as to such matters or otherwise than as the prior art and the appended claims may require.

I claim:

1. The method of making block printed 45 felt base two-tone rugs which consists in primarily coating the entire area of the carpet, block printing rug centers upon the carpet leaving the primarily coated carpet face exposed between and at the margins of the rug centers to provide rug borders, and cutting

the rugs apart between the spaced rug centers.

2. The method of making block printed 50 felt base rugs which consists in primarily coating the entire area of the carpet, block 55 printing rug centers upon a carpet leaving the carpet face exposed at all the margins of the rug centers, block printing on the rug centers and on the exposed portions of the face of the carpet with additional top print 60 patterns, and cutting the rugs apart between the spaced rug centers.

3. The method of making block printed 65 felt base rugs which consists in primarily coating the entire area of the carpet, print- 70 ing the center parts of the carpet with a block of less effective length than the width of the carpet leaving an unprinted margin at each side and interrupting such printing at intervals by putting the block out of ac- 75 tion to provide crosswise ranging stripes, then continuously printing the carpet with a block of the same effective length as the width of the carpet, and finally cutting the carpet at the stripes to provide rugs or mats. 75

4. The method of making block printed 80 felt base rugs which consists in primarily coating the entire area of the carpet, print- 85 ing the center parts of the carpet with a block of less effective length than the width of the carpet, leaving an unprinted margin at each side and interrupting such printing at intervals by putting the block out of ac- 90 tion to provide crosswise ranging stripes, and finally cutting the carpet at the stripes 95 to provide rugs or mats.

5. As an article of manufacture a two- 90 tone block printed rug comprising a felt base, a primarily coating or film co-extensive with the face of the base and consisting 95 of a paint composition appropriate for rug borders, and a rug center or center ground formed by paint deposited on the surface of the central portion of said primary coating or film, the marginal portion of primary coating or film being exposed to constitute a border or border ground around all four edges of the rug.

NEIL L. CAMPBELL.
